[57] CLAIM

The ornamental design for a caster block for coupling a stroller caster assembly to a stroller frame, as shown and described.

DESCRIPTION

FIG. 1 is a left side elevational view of a right caster leg for coupling a stroller caster assembly to the right side of a stroller frame showing our new design;

FIG. 2 is a top plan view thereof;

FIG. 3 is a right side elevational view thereof;

FIG. 4 is a bottom plan view thereof;

FIG. 5 is a front elevational view thereof;

FIG. 6 is a rear elevational view thereof;

FIG. 7 is a right side elevational view of a left caster leg for coupling a stroller caster assembly to the left side of a stroller frame;

FIG. 8 is a top plan view thereof;

FIG. 9 is a left side elevational view thereof;

FIG. 10 is a bottom plan view thereof;

FIG. 11 is a front elevational view thereof; and,

FIG. 12 is a rear elevational view thereof.
